UNITED STATES PATENT OFFICE

JOSEPH ASKIN, OF BUFFALO, NEW YORK, ASSIGNOR TO FEDDERS MANUFACTURING COMPANY, INC., OF BUFFALO, NEW YORK, A CORPORATION OF NEW YORK

RADIATOR

Application filed February 28, 1929. Serial No. 343,463.

This invention relates to a radiator which is more particularly intended for cooling the water which is circulated through the jackets of gas engines although the same may be used for other purposes.

5 In radiators of this character as heretofore constructed any vapors generated upon heating the cooling liquid usually escaped to the atmosphere. This is objectionable because, 10 not only of the loss of the water which must be replaced from time to time, but also of the loss of the vaporized alcohol or other volatile anti-freezing medium which may be contained in the cooling solution and therefore had to be replaced in order to avoid endangering the safety of the radiator in cold weather.

15 It is therefore the purpose of this invention to provide a radiator of this character with means which will condense the water and alcohol or other vapors which may be generated and collect the same in such manner that when the radiator again becomes cool these condensed vapors will be again drawn automatically back into the radiator, thereby reducing to a minimum the loss of water due to expansion, vaporization or boiling and necessitating less frequent watching and replenishing during warm weather, and also maintaining concentration of the anti-freezing solution and eliminating the necessity of frequently replenishing the alcohol or other non-freezing medium.

20 In the accompanying drawings:

25 Fig. 1 is a rear elevation of a radiator equipped with my invention.

30 Fig. 2 is a vertical section of the same taken on line 2—2, Fig. 1.

35 In the following description similar characters of reference indicate like parts in both figures.

The numeral 10 represents the cellular core of radiator which may be of any usual or well known construction so as to divide the cooling water into fine streams and thus permit the currents of air to abstract the heat therefrom more readily. Secured to the upper end of the core and communicating with the upper ends of the water passages thereof is an

40 let nipple 12 on its rear side for connection with the conduits whereby the heated water is conducted from the jacket of the engine cylinders to the radiator.

45 On top of the upper header is arranged a filler 13 through which the water for cooling the engine and also any anti-freezing medium, such as alcohol, is introduced into the radiator, this filler being normally closed or sealed so as to be air tight by means by a 50 screw cap 14, or similar means.

55 At its lower end the core has secured thereto a lower water header or box 15 which communicates with the lower ends of the water passages thereof and is provided with a water outlet nipple 16 which is connected by a 60 conduit with the water jacket of the cylinders as part of the cooling water circulating system.

65 Heretofore any vapors generated by heating of the water and alcohol or other vaporizable medium therein was discharged to the atmosphere and lost. In the present case, however, such vapors are condensed and the condensate collected and stored in such manner that the same are available for further use.

70 Although the means for accomplishing this result may be variously constructed the same are so organized that they form an integral 75 unit with the radiator proper and can be incorporated in the standard forms of radiators now commonly used without requiring any material alteration in the construction of the same.

75 In the preferred embodiment of this invention, as shown in the drawings, the same comprises a condensate tank 17 secured to the rear side of the lower header or water box. A vapor or overflow pipe 18 is provided 80 which has its upper part arranged in the upper header and its upper end terminating within the upper part of the filler forming part of the upper header and its lower end soldered tightly at 25 to the top of the condensate tank and extending to the lower part of the condensate chamber at one end thereof while its intermediate part is arranged along 85 one side of the core.

90 Communication with the outer atmosphere 95

100 upper water box or header 11 which has an in-

is provided by a vent pipe 19 which connects with the top of the condensate chamber adjacent to the opposite end of the same and extends downwardly along the adjacent part of this chamber.

In the operation of this radiator the water entering the upper header passes downwardly through the core so as to be cooled and is then returned to the engine jacket in the usual manner.

Any vapors given off from the heated water or alcohol are discharged by the internal pressure within the radiator through the vapor pipe 18 into the condensate chamber whereby these vapors are condensed and the resulting liquid collected in the condensate chamber. If the condensate should exceed in quantity the capacity of the condensate chamber any excess condensate will escape from this chamber through the vent pipe 19 to the exterior of the radiator.

When the radiator subsequently cools off a vacuum is created therein which causes the liquid in the condensate chamber to be sucked back from this chamber into the radiator proper and mixed with the liquid therein.

It will be apparent therefore that by these means the vapors given off from the cooling liquid in the radiator will be retained and saved ready to be returned automatically to the water circulating system when the temperature of the circulating cooling liquid has lowered sufficiently. No material loss of water therefore occurs due to the expansion, vaporization or boiling of the water so that the attention required for keeping the radiator filled with water is minimized.

Moreover, the saving of the alcohol vapors and the automatic return of the same to the radiator operates to maintain the concentration of the anti-freezing medium in the solution and eliminate unduly frequent replenishment of the supply of the alcohol or similar liquid.

Obviously the most successful operation of this invention is dependent on making the joint between the filler and its cap air tight fit.

Inasmuch as this invention is applicable to radiators of standard construction the same can be installed without material alteration at comparatively small cost.

I claim as my invention:

The combination with a unitary radiator including an upper header, a lower header and a cooling section communicating at its upper and lower ends with said upper and lower headers, said headers and cooling section together extending the full height, width and depth of the radiator, of a compensating system associated with said radiator and connected therewith as an attachment thereto and arranged wholly outside of the space usually occupied by the radiator and comprising a condensing chamber arranged in

rear of the lower header and attached thereto and having its top below the lower end of said cooling section and provided in its upper part with a vent leading to the atmosphere, and a vapor delivery and liquid return pipe arranged in rear of said cooling section and communicating at its upper end with the upper part of said upper header and communicating at its lower end with the lower part of said condensing chamber.

In testimony whereof I hereby affix my signature.

JOSEPH ASKIN.
